D11-151. OR D13,255 EX

No. 13,255

Aug 22, 1882

UNITED STATES PATENT OFFICE.

CHARLES O. HELD, OF COLUMBUS, OHIO.

DESIGN FOR A FLOWER-VASE.

SPECIFICATION forming part of Design No. 13,255, dated August 22, 1882.

Application filed July 14, 1882. Term of patent 7 years.

To all whom it may concern:

Be it known that I, CHAS. O. HELD, of Columbus, in the county of Franklin and State of Ohio, have invented certain new and useful 5 Improvements in Designs for Flower-Vases; and I do hereby declare the following to be a full, clear, and exact description of the invention, such as will enable others skilled in the art to which it pertains to make and use it, reference 10 being had to the accompanying drawing, which forms part of this specification.

My invention relates to an improvement in designs for flower-vases; and it consists in a vase which is made in the shape of a rose or 15 other flower, and which is placed upon the top of a stem from which extend a number of branches, as will be more fully described hereinafter.

The accompanying photograph represents a 20 side elevation of my invention.

A represents the drip-pan or base, from the top of which rises the stem B, from the side of which extend two or more branches, C, which have a number of leaves, D, upon them.

On the top of the stem is the vase F, which is 25 shaped like a flower, and which is open at its top, so as to receive the flowers or plants which are to be planted therein. This vase may be painted or colored to correspond to the flower or fruit it is to represent.

30 A vase of the form here shown presents a very pretty and attractive appearance, and lends very materially to the beauty of a yard or garden in which it is placed.

Having thus described my invention, I 35 claim—

A design for a flower-vase, consisting in the combination of a base, a stem, the side branches, and the vase made in the form of a flower, as 40 shown.

In testimony whereof I affix my signature in presence of two witnesses.

CHARLES O. HELD.
